UNITED STATES PATENT OFFICE.

HENRY C. KEELER, OF LAKESIDE, WASHINGTON.

PORTABLE FIREPLACE.

1,178,854.

Specification of Letters Patent. Patented Apr. 11, 1916.

Application filed September 9, 1914. Serial No. 860,902.

To all whom it may concern:

Be it known that I, HENRY C. KEELER, a citizen of the United States, residing at Lakeside, in the county of Chelan and State of Washington, have invented certain new and useful Improvements in Portable Fireplaces, of which the following is a specification.

My invention relates to new and useful 10 improvements in fire places and more particularly to what is known as a portable fire place.

The primary object of the invention is the provision of a fire place which may be moved from place to place and which provides different compartments for the heating and cooking of various articles.

A further object of the invention is the construction of such a fire place having a 20 plurality of doors which may be so adjusted as to disclose an open fire place or which may be closed to provide various drafts.

With these and other objects in view the invention consists in the novel details of 25 construction and arrangement of parts which will be more clearly understood from the following description and drawings, in which:

Figure 1 is a front view. Fig. 2 is a detail of one door section. Fig. 3 is a vertical section, and Fig. 4 is a fragmental side view.

In constructing the device I provide a casing consisting of a top plate 1, a rear plate 2, a bottom plate 3, end plates 4 and 35 a front plate 5 which only extends a short distance downward from the top plate 1, the remainder of the distance being open. The plate 6 is secured to the back of the casing and a plate 7 to the bottom plate 40 and an asbestos filling 8 is placed between the plates 2 and 6, and 3 and 7.

The front opening in the casing is adapted to be closed by a plurality of door sections 9 which are hingedly connected to the 45 ends of the casing by means of the plates 10 which are also pivotally connected to the door sections by means of rods 11 which pass through sockets 12 formed on the door sections and through an eye 13 formed on 50 the plates 10. The door sections are each of a width equal to the width of the end plates 4, whereby when they are open to their fullest extent they will lie against the end sections without any protruding ends. 55 A plate 14 having the chamber 15 therein

opening into the casing is secured to the bottom plate 3 and extends in front of the casing. This plate 14 is provided with an opening 16 in the top thereof which allows air to pass through the chamber 15 into the 60 casing. Within the casing and supported on the bottom thereof are andirons 17 or a grate for coal may be used. A compartment 18 extends transversely of the casing and openings are formed in each end of the casing as indicated, at 19, and doors 20 similar to the front doors are hingedly connected to the casing and adapted to close the openings in the ends. Within the compartment are a plurality of shelves 21 to receive various 70 articles. The compartment is so placed in the casing as to allow an opening or passage 22 in the rear thereof and at the top of the opening is a damper 23 which is adapted to be operated from the outside of the casing. 75 A smoke stack 24 extends from the top of the casing.

In constructing a device, as above described, it will be seen that I have provided a fire place which is easily portable from one 80 place to another and in which by opening and closing the various doors a greater or less draft may be secured. Normally there is a slight draft through the opening 16 in the plate 14 and if it is desired to get a 85 greater draft the lower doors may be opened. By regulating the damper 23 the passage of the heat through the opening 22 may be regulated. The compartment 18 may be used for cooking various articles and the 90 articles may be placed within the compartment or removed therefrom by opening the doors 20. When the front doors 9 are open they swing back against the end pieces and do not protrude beyond the front or rear 95 walls of the casing. It will also be seen that by providing the asbestos lining in the rear and bottom of the casing it prevents too great a heat against a wall which may be near the fire place or prevents too great a 100 heat on the floor. By opening all of the doors I may have an open fire place.

Having fully described my invention what I claim as new and desire to secure by Letters Patent is:—

1. A portable fire-place comprising a casing having an open front and chimney, doors hingedly connected to the casing for closing said open front, the rear wall of said casing extending above the top wall 110

thereof and rolled to form a chimney, and a compartment arranged transversely of the casing and spaced from said wall.

2. A portable fire-place comprising a casing having an open front, means for closing said front, a compartment arranged transversely of the casing, the rear wall of said compartment spaced from and the front wall of the compartment secured to the rear wall of the casing, the front wall having an opening therethrough alining with the passageway thus formed between the rear walls,

a damper on the upper wall of the compartment to close said passageway, an asbestos filling between the bottom of the casing and 15 a plate spaced therefrom, and an asbestos lined plate spaced from the back plate of the casing.

In testimony whereof I affix my signature in presence of two witnesses.

HENRY C. KEELER.
